UNITED STATES PATENT OFFICE

2,506,085

BOAT-LOWERING APPARATUS

William Lewis Howard, London, England, assignor to Welin-Maclachlan Davits Limited, London, England

Application July 2, 1945, Serial No. 602,712
In Great Britain March 15, 1944

Section 1, Public Law 690, August 8, 1946
Patent expires March 15, 1964

2 Claims. (Cl. 9—30)

1

This invention relates to boat lowering apparatus.

At the present time lifeboats are usually lowered from a winch controlled by a main lowering brake which is actuated by an operator, the winch being situated on the ship's deck. With such an arrangement, if the ship is on fire, the deck may become so hot that the operator is unable to remain on the deck to control the winch brake; furthermore the operator frequently cannot see the boat which he is lowering but has to depend upon orders given to him from a remote point; as a result it is more difficult for the operator to lower the boat at the correct moment onto a wave than it would be if he could see the boat all the time he is lowering it.

According to the present invention a lifeboat or other boat to be lowered from a winch on a ship's deck is provided with a control device whereby the lowering of the boat can be controlled from the boat itself, thus dispensing with the need for an operator at the winch.

In one form of construction the control device consists of a self-contained unit which can be fitted to the boat blocks, or fixed in any suitable position in the boat and comprises a bracket carrying a drum freely mounted thereon. The drum is provided with a handwheel at one end, outside the bracket, and a brake drum which can be controlled by a brake lever on the other end. A small diameter rope preferably of flexible steel wire is wound in layers on the drum, the length of rope being determined by the height of the boat deck above the low water line. The rope is taken optionally over a sheave on the top block (in the case of ordinary boat tackle), or over a sheave attached to the davit itself and thence down to the winch brake lever as directly as possible by any suitable means.

In order to prevent the rope from whipping or becoming in any way too slack when the boat is being normally controlled by the winch brake, provision is made for maintaining a slight permanent friction on the brake drum of the control device, preferably by means of a totally enclosed spring loaded lever, the spring being easily adjustable by hand, or the friction may be obtained by means of a counter-weight on the brake lever. When hoisting the boat the rope can be easily rewound on the drum by turning the handwheel to take up the slack as the boat is hoisted. If preferred the brake unit can be fitted in the boat itself, in which case the rope is not permanently anchored to the drum but is so arranged as to be free to unwind completely off the drum when the boat is rowed away.

2

In the accompanying drawings which illustrate the invention:

Figure 1 is an elevation;

Figure 2 is an elevation at right angles to Figure 1;

Figure 3 is a detail elevation of a modification;

Figure 4 shows diagrammatically in elevation the application of the invention shown in Figure 3; and

Figure 5 is a detail elevation at right angles to Figure 4 on a larger scale.

Referring more particularly to Figures 1 and 2, 1, 2 are top and bottom blocks respectively for lowering a boat. Secured to the block 2 is a U-shaped bracket 3. Rotatably mounted in bearings on the arms of the bracket 3 is a spindle 4 having fast thereon a drum device 5 and a brake drum 6 between the arms of the bracket 3, and a hand wheel 7 outside the bracket 3. 8 is a spindle which is rotatably mounted in bearings on one of the arms of the bracket 3 and a third arm 3'. Mounted on the spindle 8 is a brake lever 9. 10 is a brake band secured at one end to the brake lever 9 at or near one end thereof, the other end of the brake band being secured to the brake lever 9 at 11. 12 is a counterweight for maintaining a slight friction on the brake drum 6. 13 is a flexible steel wire rope or cable of small diameter which is wound in layers on the drum 5 and is taken over a sheave 14 to the lever of the main lowering brake of a winch on the ship's deck as directly as possible by any suitable means e. g. as described in Figures 4 and 5. The counterweight 12 only maintains sufficient tension to prevent the rope 13 from whipping or becoming too slack but is not sufficient to release the brake on the ship's winch when it is desired to lower the boat, i. e. the brake is normally ineffectively applied.

In the modification shown in Figure 3 the counterweight 12 is replaced by a light spring 15 which acts on a rod 16 pivotally connected at 17 to an extension of the brake lever 9.

In the modification shown in Figures 4 and 5, the control device shown in Figure 3 is mounted on a block 18 which supports a boat 19 and is carried by a hook 20 on or near to the end of a davit 21 of known construction, the rope 13 passing over a sheave 22 on the end of the davit 21, over a sheave 23 on the davit 21 and thence over a sheave 24, and round a sheave 25 to the underside of a lever 26 which actuates the main lowering brake 27 of a winch 28 which is located as usual on the ship's deck and controls the lowering of the boat 19 so that when tension is applied to the rope 13 the brake lever 26 is pulled

downwards and the main lowering brake 27 is released. Obviously if the winch 28 is provided with a main lowering brake which is released by raising the lever 26 the rope 13 would be led directly to the brake lever 26 instead of round a sheave 25.

It will be seen that when the handwheel 7 is turned positively in a direction to wind the rope 13 on the drum 5 the rope 13 will pull the winch brake lever 26 and open the brake 27 on the winch 28. Simultaneously with operating the handwheel 7 to open the winch brake 27, the operator must positively hold the brake lever 9 on the control device and apply sufficient friction on the brake drum 6 to maintain the required tension in the rope 13 necessary to keep the winch brake 27 open. Thus the rope 13 is conditioned for releasing the winch brake by the operator's positively actuating the hand wheel 7 to tension the rope. If the operator, either on purpose or accidentally, does not apply sufficient friction on the brake drum 6 by means of the brake lever 9, the boat 19 will come to a standstill, and the hand wheel 7 must be turned again in a direction to wind the rope 13 on the drum to open or release again the brake 27 on the winch 28 to allow the lowering of the boat to re-commence.

The operator will readily adapt himself to the "feel" of the operation and after a little experience will be able to lower the boat 19 quite comfortably without stalling.

If it be desired to lower the boat 19 in the normal manner from the ship's deck, the operator can effect this by depressing the brake lever 26 to release the main lowering brake 28, and the rope 13 is prevented from becoming slack by the friction imposed on the brake drum 5 of the control device by the counterweight 12 (Figure 2) or the spring 15 (Figure 3).

What I claim is:

1. Apparatus for effecting lowering of a ship's life boat or other boat under the control of an operator in the boat, comprising a winch on the ship; lowering connections between said winch

and said boat; a normally applied winch brake; a cable connected to said brake and adapted when tensioned to release the brake; and a control device on said boat comprising a drum to which said cable is connected, a normally ineffectively applied brake for said drum, and means accessible to the operator in the boat for controllably applying said drum brake effectively during lowering of said boat to enable said drum to pay out said cable under tension sufficient to effect controlled releasing of said winch brake.

2. Apparatus for effecting lowering of a ship's life boat or other boat under the control of an operator in the boat, comprising a winch on the ship; lowering connections between said winch and said boat; a normally applied winch brake; a cable connected to said brake and adapted when tensioned to release the brake; and a control device on said boat comprising a drum to which said cable is connected, a hand wheel connected to said drum and being positively actuatable by the operator for applying initial tension to said cable to thereby release said winch brake and enable the boat to be lowered, a normally ineffectively applied brake for said drum, and means accessible to the operator in the boat for controllably applying said drum brake effectively during lowering of the boat to enable said drum to pay out said cable under tension sufficient to maintain said winch brake controllably released.

WILLIAM LEWIS HOWARD.
